(57) **CLAIM**

The ornamental design for flow regulator, as shown and described.

DESCRIPTION

4. Flow regulator
4.1 : Top
4.2 : Perspective
4.3 : Bottom
4.4 : Perspective
4.5 : Front
4.6 : Back
4.7 : Left
4.8 : Right

The broken lines represent portions of the Flow Regulator that form no part of the claimed design.
